UNITED STATES PATENT OFFICE

JAMES E. CONNOLLY, OF BALTIMORE, MARYLAND

SAFETY RAZOR

Application filed August 17, 1929. Serial No. 386,651.

The invention generally relates to razors of the type disclosed in Patent No. 1,651,917, issued to me on Dec. 6, 1927, and in application Serial No. 273,560 filed by me on April 28, 1928, in which are embodied the customary handle, clamp plate, guard plate, blade and blade guard and lather working rollers and regulating devices, and primarily has for its object to provide certain new and useful improvements in the construction and arrangement of said parts rendering the manufacture of the articles simpler and less expensive and greatly facilitating the use of the razors and the cleansing thereof after use.

An object of the invention is to provide a novel, simplified form of lather reapplication regulating means.

Another object of the invention is to provide a guard plate on which the guard and reapplication rollers are so mounted as to enable the use of the plate, either individually or collectively with remaining parts of the razor as a novel massaging implement.

Another object of the invention is to provide guard plate roller bearing lugs with steps where overlapped by the blade to enable full use of the cutting edges from end to end.

Another object of the invention is to provide a novel hollow, double ended handle greatly facilitating assembly, disassembly and cleansing of the razor and permitting the convenient storage of first aid preparations in the handle when desired.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawings, in which:

Figure 1 is a perspective view illustrating the invention mounted on a razor of well known type.

Figure 2 is an inverted plan view of the

head of the razor, the handle being removed. Figure 3 is a cross section taken on the line 3—3 of Figure 2.

Figure 4 is a perspective view of the regulator member.

Figures 5 and 6 are end and side views respectively of the regulator shown in Figure 4.

Figure 7 is an enlarged detail perspective view of a corner of the guard plate showing the blade clearing lug cut-out.

Figure 8 is an end view of the razor.

Figure 9 is an end view illustrating the use of the razor as a massage implement.

Figure 10 is a detail end view illustrating the use of the guard plate alone as a massage implement.

Figure 11 is a detail view, part elevation and part sectional, illustrating a hollow double ended handle.

Figure 12 is a detail longitudinal section of a handle equipped for encasing first aid medicinals or the like.

Figure 13 is a plan view of a modified form of regulator member.

Figure 14 is a fragmentary perspective view illustrating the manner of mounting the modified form of regulator on the guard plate.

In the drawings 1 designates the razor handle to which the clamp head is attached, said handle being provided with a threaded socket 2 to receive the threaded shank 3 of the clamp head 4.

The guide lugs 5 of the clamp head pass through suitable receiving apertures in the guard plate 6 which is also provided with an aperture to receive the shank 3. Between the guard plate 6 and the clamp head 4 the usual double edged blade 7 is clamped in the manner illustrated in Figure 1 of the drawings.

All of the above structure will be recognized as conventional and it is to be understood that while I have disclosed the invention as applied to this particular form of razor the invention is not so limited in application and comprehends all structures coming within the scope of the appended claims.

In the practical development of the in-

vention the side edges of the guard plate are preferably cut out to provide opposed pairs of mounting lugs 8 which provide trunnion bearings 9 for the guard rollers 10, one there-
 5 of being mounted at each side of the guard plate. The cut out portions of the plate 6 are deep enough to provide an appreciable space 11 between each roller 10 and the adjacent plate edge to permit free lather pas-
 10 sage and free rotation of said rollers.

Each guard roller 10 is preferably pro-
 vided with a grooved face engaging surface,
 the grooves being arranged in reversed spirals
 12 so as to diverge from or converge to a
 15 point intermediately of the ends of said roller
 thus forming centrally disposed V's 13, see
 Figures 1 and 2.

It will be observed by reference to Figures
 7 and 8 that the trunnion lugs 8 are stepped
 20 down as at 14 beneath the blade engaging
 surface of the guard plate to enable the blade
 to overhang clear of the lugs. Thus the
 shaving edges of the blade are not inter-
 rupted at the ends by the lugs and it is there-
 25 fore possible to employ the extreme corners
 of the blade in effecting accurate trim-shav-
 ing operations which are desirable and in
 fact necessary around the regions of the ears
 and temple as well as when trimming a
 30 mustache.

One of the principal objects of my present
 invention is to simplify the structure dis-
 closed in my application for patent Serial
 Number 273,560 filed April 28, 1928, and to
 35 provide a razor structure capable of being
 quickly and conveniently assembled and dis-
 assembled for cleaning or the like.

To this end I provide a simple regulator
 unit or member generally designated 15 and
 40 illustrated in detail in Figures 4, 5 and 6.
 This regulator is of the stationary fixed ad-
 justment type adapted to be held against the
 guard plate in a single, fixed operative pos-
 45 tion assuring proper cooperative relation of
 the parts without danger of misadjustment
 due to vibration or shock.

The regulator member is preferably formed
 of thin but strong spring sheet metal and
 comprises a central cross web or body 16
 50 apertured at 17 to receive the clamp head
 shank 3, and at 18 to receive the guide lugs 5
 of said clamp head. The sides of the regu-
 lator beyond the body 16 are bent downward-
 55 ly-outwardly as at 19 and are cut out as at 20
 to make the regulator light and flexible and
 to provide regulator side bars 21.

The regulator side bars 21 are preferably
 curved slightly as at 22 to conform to the
 curvature of the rollers and provide con-
 60 centric lather passing spaces of fixed dimen-
 sion. These bars are also bowed slightly
 away from rollers at their central portion
 as at 23 to tend to localize the lather at that
 point, and at their extreme corners, they are
 65 preferably cornered-in as at 24 to overlia a

portion of the roller ends and tend to thwart
 dripping of lather off the roller ends.

The end edges of the regulator are turned
 as at 25 to provide finger grips which greatly
 facilitate mounting and removal of the regu-
 70 lator, and to further provide for mounting
 the regulator, especially upon the guard plate
 6, the regulator is provided with notches 26
 arranged in the corners provided by the cut-
 outs 20 and adapted to snap over the snap
 75 head pins 27 which depend from the con-
 cave face of the guard plate. Thus the regu-
 lator may be removed bodily with the guard
 plate or readily separated therefrom as de-
 sired.

With this type of regulator unit the re-
 application of lather is properly regulated,
 the lather is well worked and concentrated
 at the center of the instrument and a con-
 struction is provided which can be quickly
 85 and conveniently assembled for use and dis-
 assembled for cleansing and storage purposes.

It will be found that the grooved roller
 equipped guard plate alone may be employed
 as an efficient skin massaging implement.
 For this purpose the ends of the plate may
 be roughened or seated as at 28 to provide
 90 finger grips. The rollers being reversely
 grooved, the combined massage effect is dif-
 ferent than a single roller massage because
 where a single roller will roll back and forth
 in the same grooves the following roller of a
 95 cooperating pair will work the lather or mas-
 sage cream oppositely of the function of the
 advance roller so that a vigorous continuously
 reversing spreading of the cream or lather
 100 is brought about and a real health giving
 massage assured. See Figure 10.

By reversing the position of the guard
 plate and eliminating the blade and regu-
 lator member as shown in Figure 9, a very effi-
 105 cient massage implement is provided. The
 rollers provide for a sort of anti-friction
 massage and lather working operation, and
 between them the smooth clamp head fric-
 tionally engages the face providing a com-
 110 bined friction and anti-friction massage. It
 will be understood, of course, that the clamp
 head is narrow enough to fit between the
 rollers without interfering with their free
 115 rotation.

The razor handle is preferably made hol-
 low as at 29 and double ended as shown at
 120 30 in Figure 11 to facilitate assembly and
 thorough cleansing. Persons who find it
 necessary to wear eye-glasses for example,
 having removed them to shave, often find it
 difficult to locate the socketed end of the
 125 razor handle and consequently lose much
 time in assembling the razor. In addition
 to the ease of assembly afforded by the dou-
 ble end sockets, the tubular construction en-
 ables the passage of hot water through the
 130 handle and thus makes it possible to keep the

sockets free from germs and matter upon which germs could feed.

In Figure 12 I have shown another modified form of handle which is provided with 5 a hollow socket 31 which may be lined at 32 with rubber, baked enamel or the like and suitably sealed air and moisture tight by a screw plug as shown. The handle thus constructed may serve as a receptacle for first 10 aid medicinal preparations such as styptic stick, mercuro-chrome or iodine vial, anti-septic tablets or the like, which preparations, thus always present for immediate use, will assure against infections often resulting 15 from razor cuts.

In Figures 13 and 14 I have disclosed a modified form of regulator member in which the cross web is cut out as at 33 to clear the 20 clamp head screw shank and guide lugs and is provided with end extensions 34 bent to form mounting lugs which may be sprung into recesses 35 provided in the ends of the 25 guard plate and serve as a simple means for holding the regulator member in operative position.

From the foregoing description taken in connection with the accompanying drawings, it is thought that the novel details of construction, the manner of use and the advantages of the invention will be readily apparent to those skilled in the art to which the invention relates.

I claim as my invention:

1. In a razor wherein is provided a cutting 35 edge and an edge guard and lather reapplicator mounted in associated relation with the cutting edge to guard the same and to reapply lather to the face of a user adjacent said cutting edge, and means to regulate the 40 reapplication of lather comprising a bar positioned in close spaced relation to said reapplicator and having the central portion thereof spaced a greater distance from said reapplicator than are its ends.

2. In a razor wherein is proved a cutting edge and an edge guard and lather reapplicator roller rotatably mounted in associated 45 relation with the cutting edge to guard the same and to reapply lather to the face of a user adjacent said cutting edge, and means to regulate the reapplication of lather comprising a bar positioned in close spaced relation to said reapplicator, said bar being bowed away from said roller at its central 55 portion for the purpose described.

3. In a safety razor, the combination with a guard plate, of a blade mounted in operative position on the guard plate, a roller mounted on the guard plate in associated 60 relation with the blade to guard its cutting edge and to reapply lather to the face of a user adjacent the blade cutting edge, a lather reapplication regulator member, and spring snap means to mount the regulator member 65 on the guard plate for individual removal or

for removal together with the guard plate.

4. In a razor wherein is provided a cutting edge and an edge guard and lather reapplicator roller rotatably mounted in association with the cutting edge to guard the same and to reapply lather to the face of a user adjacent said cutting edge, and means to regulate the reapplication of lather comprising a bar positioned in close spaced relation to said reapplicator, and having its ends extended 70 beyond and turned toward the roller ends for the purpose described. 75

5. In a razor wherein is provided a cutting edge and an edge guard and lather reapplicator roller rotatably mounted in associated 80 relation with the cutting edge to guard the same and to reapply lather to the face of a user adjacent said cutting edge, and means to regulate the reapplication of lather comprising a bar positioned in close spaced relation to said reapplicator, said bar being bowed away from said roller at its central portion and having its ends extended beyond 85 and turned toward the roller ends for the purpose described. 90

6. In a razor wherein is provided a cutting edge and an edge guard and lather reapplicator roller rotatably mounted in associated 95 relation with the cutting edge to guard the same and to reapply lather to the face of a user adjacent said cutting edge, and means to regulate the reapplication of lather comprising a bar positioned in close spaced relation to said reapplicator, said bar having a portion extended in concentric relation with the roller to provide therewith a concentric lather passage regulating space. 100

7. The combination with a guard plate having its side edges recessed to provide trunnion lugs, and a roller rotatable in each edge recess and having trunnion bearing in the lugs, of a lather reapplication regulator comprising a body and regulator bars extended laterally into close proximity to the rollers, and means to removably mount the regulator 105 on the guard plate. 110

8. The combination with a guard plate having its side edges recessed to provide trunnion lugs, and a roller rotatable in each edge recess and having trunnion bearing in the lugs, of a lather reapplication regulator comprising a body and regulator bars extended laterally into close proximity to the rollers, and means to removably mount the regulator on the guard plate. said last named means comprising interengaging spring members and detents enabling assembly and disassembly of the plate and regulator by spring snap action. 115

9. The combination with a guard plate having its side edges recessed to provide trunnion lugs, and a roller rotatable in each edge recess and having trunnion bearing in the lugs, of a lather reapplication regulator comprising a body and regulator bars ex- 125 120 130

tended laterally into close proximity to the rollers, said bars having the portions thereof adjacent the rollers shaped concentric to the axes of the rollers, and means to removably mount the regulator on the guard plate.

5 10. The combination with a guard plate having its side edges recessed to provide trunnion lugs, and a roller rotatable in each edge recess and having trunnion bearing in the lugs, of a lather reapplication regulator comprising a body and regulator bars extended laterally into close proximity to the rollers, said bars having the portions thereof adjacent the rollers shaped concentric to the axes of the rollers, and being bowed slightly away from the rollers at their central portions, and means to removably mount the regulator on the guard plate.

10 15 20 25 30 11. The combination with a guard plate having its side edges recessed to provide trunnion lugs, and a roller rotatable in each edge recess and having trunnion bearing in the lugs, of a lather reapplication regulator comprising a body and regulator bars extended laterally into close proximity to the rollers, said bars being bowed slightly away from the rollers at their central portions and having their end corners extended beyond and turned toward the ends of the rollers for the purpose described, and means to removably mount the regulator on the guard plate.

In testimony whereof, I have hereunto subscribed my name.

35 JAMES E. CONNOLLY.
